PLEASURE-WHEEL.

No. 881,095.

Specification of Letters Patent.

Patented March 3, 1908.

Application filed October 15, 1907. Serial No. 397,584.

To all whom it may concern:

Be it known that I, ELTON F. CHUBBUCK, a citizen of the United States, residing at Hornell, in the county of Steuben and State 5 of New York, have invented certain new and useful Improvements in Pleasure-Wheels, of which the following is a specification.

My invention relates to pleasure devices and particularly contemplates the provision 10 in a novel and simple construction of pleasure wheels, which will be useful and durable, without danger to the pleasure seekers.

My invention further and specifically resides in the following features of construction, arrangement and operation which will be hereinafter described with reference to the accompanying drawings, forming a part of this specification, in which like numerals are used to designate like parts throughout 20 the several figures, and in which,

Figure 1 is a side elevation of my improved apparatus, and Fig. 2 is a central vertical sectional view taken therethrough.

In the practical embodiment of my invention I provide a pleasure device comprising a wheel 1 having a central shaft 2 provided with hubs 3 adjacent the ends thereof. The peripheral rim of the wheel 1 is composed of a T-shaped rail 4 bent in an 30 irregular form about the shaft 2 and having its central rib extending inwardly therefrom and secured by radially extending spokes 5 through the hubs 3. To strengthen the structure just described, I preferably arrange 35 circular braces 6 against and attached to each of the spokes 5 between the shaft 2 and the rim 4. The T-rail, forming the rim 4 is, according to my invention, bent and secured around the shaft 2 in a form other than that 40 of a true circle, and, while I have shown in the accompanying drawing said rim 4 as bent to a rectangular shape having rounded corners, as a preferred form, it will be understood that I may as readily and with the 45 same purpose in view form the same oval or any other irregular shape.

The wheel 1 is supported above the ground to be freely rotated, upon a supporting frame comprising triangular side frames 50 7, the upright members of which are connected by braces 8, and which have bearings 9 secured upon their upper ends in which the projecting ends of the shaft 2 are journaled. To rotate the wheel 1 I preferably secure 55 upon the shaft 2 between one of its hubs 3 and the adjacent bearing 9, a worm gear 10,

gravity thereupon, as their rail, substantially as described.

3. In a pleasure wheel of the character described, the combination of a supporting stand, a freely rotating wheel having its shaft 5 journaled upon said stand, the peripheral rim of said wheel being formed in an irregular shape about said shaft and constituting a rail, and a hanging car adapted to be actu-

and I also suitably journal through supporting brackets 11 extending from one of the supporting side frames 7, an upright driven shaft 12 having a worm 13 formed upon its upper end and in engagement with the worm gear 10. The shaft 12 being driven from a suitable source of power will cause rotation of the wheel shaft 2 by means of the gears 13 and 10 and will therefore rotate the pleasure 60 65 wheel 1.

Any suitable car 14 may be employed adapted to seat a number of people capable of correctly balancing the same and is provided with a yoke frame 15 universally connected thereto at 16, said yoke frame carrying rotatably mounted in its ends flange wheels 17 straddling the rim 4 of the pleasure wheel 1 and adapted to freely travel upon the extending flanges of the T-rail forming 70 75 said rim 4.

In the practical operation of my invention, the wheel 1 is rotated at such speed that the car 14 will roll by gravity upon the flat portions of the rim 4 and will be carried in the 80 direction of rotation of said wheel by the rounded corners to again roll, at the same time receiving an up and down movement and a shaking movement which are the desired ones in a device of this character. 85

Having thus fully described my invention, I claim:

1. In a pleasure device of the character described, the combination of a supporting stand, a freely rotating wheel having its 90 shaft journaled upon said stand, the peripheral rim of said wheel being formed in an irregular shape about said shaft and constituting a rail, and a car adapted to be actuated upon the rotation of said wheel, having 95 wheels rotatably journaled within a portion thereof and straddling said rim and freely rolling by gravity thereupon, substantially as described.

2. In a pleasure device of the character described, the combination of a supporting stand, a freely rotating wheel having its shaft suitably journaled upon said stand and provided with hubs mounted thereon adjacent its ends, the peripheral rim of said wheel 105 being formed in a substantial rectangular shape about said shaft and connected thereto by radial spokes, said rim having continuous outstanding flanges, and a car having oppositely disposed rollers rotatably journaled in 110 a portion thereof and adapted to straddle the flanges of said rim and to freely roll, by

10
ated upon the rotation of said wheel, having wheels to rotate freely upon said rail, substantially as described.

In testimony whereof I affix my signature in presence of two witnesses.

ELTON F. CHUBBUCK.
